UNITED STATES PATENT OFFICE.

LEROY S. BUFFINGTON, OF MINNEAPOLIS, MINNESOTA, ASSIGNOR TO
BUFFINGTON LIGHT COMPANY, OF NEW JERSEY.

ACETYLENE-GAS-GENERATING LAMP.

SPECIFICATION forming part of Letters Patent No. 677,984, dated July 9, 1901.

Application filed June 28, 1897. Serial No. 642,591. (No model.)

To all whom it may concern:

Be it known that I, LEROY S. BUFFINGTON, a citizen of the United States, residing at Minneapolis, in the county of Hennepin and State 5 of Minnesota, have invented certain new and useful Improvements in Acetylene-Gas Lamps; and I do hereby declare the following to be a full, clear, and exact description of the invention, such as will enable others skilled in 10 the art to which it appertains to make and use the same.

My invention relates to devices for the generation and use of acetylene gas, and has for its general object to improve the same with 15 a view of securing increased efficiency.

My improvements are especially serviceable in acetylene-gas lamps intended for outside or rough usage, such as on bicycles, carriages, &c.

20 To the ends above noted my invention consists of the novel devices and combinations of devices hereinafter described, and defined in the claims.

When carbid slakes, it increases in bulk, 25 or, more accurately stated, the debris or slaked lime, which is the residue from the reaction between the carbid and the water, is larger in quantity or bulk than the original carbid.

It is the custom to employ in lamps carbid 30 in the granular form or in small lumps, and if this kind of carbid is not held in a compact mass the lamp must sit still or be very carefully handled in order to secure an even generation and a perfectly steady light. If the 35 lamp is shaken or unsteadily carried about, the generation of gas will not be uniform and the light will vary in size of flame. To meet these conditions, I provide a yielding part for use within the generating-chamber, which 40 yielding part operates to hold the carbid in a compact mass and permit the residue to expand. I was the first to make any such provision for any such purpose, and hence this feature of the invention is pioneer in character. 45

The reaction between carbid and water is instantaneous. Otherwise stated, the generation is extremely quick. If water be permitted to flow or drop directly onto the car- 50 bid or the carbid be dropped directly into the water, the gas will be produced with a sud-

den gush or jump, and unless some provision be made to avoid the same the result of such sudden generation will be a jumping light. To avoid this difficulty, I provide a body of 55 absorbent material, such as blotting-paper, adapted to receive a regulated quantity of feed-water and to distribute the same to the carbid in a finely-divided condition. I was the first to so employ an absorbent material, 60 but first disclosed the same in an earlier application, which matured into my Patent No. 621,217, of date March 14, 1899, wherein said feature is broadly claimed. In the present application, however, I first disclosed absorb- 65 ent material for such a purpose, with the absorbent material located in direct and extended contact with the carbid.

It is well known that acetylene gas has a pungent acid-like odor, which is pervasive, 70 penetrating, and unpleasant to human beings if continued for any considerable time. Hence it is desirable to have means for quickly charging a lamp or other generator with the carbid in such a manner as to entirely avoid or 75 minimize the escape of the gas. Moreover, the debris or slaked carbid is sticky when fresh and hard when dry, and hence the lamp is difficult to clean if the carbid-holder be a part of the fixed structure. To meet these con- 80 ditions, I provide an expandible charge-holder adapted to be preloaded with carbid and han- 85 dled as a cartridge for charging the lamp or other generator. I was the first to provide any such charge-holder capable of use as a cartridge and adapted to expand under the increase of the bulk as the carbid slakes when the cartridge is in use in the lamp or other generator. Hence this expandible charge- 90 holder is another feature of invention which is of pioneer character.

Lamps containing the several features above noted are peculiarly well adapted for use on bicycles, carriages, and wherever liable to be shaken or otherwise subjected to 95 rough usage.

All the said features above noted may of course take manifold forms.

Several embodiments of my invention are illustrated in the accompanying drawings, 100 wherein like notations refer to like parts throughout the several views.

In said drawings, Figure 1 is a view in side elevation illustrating a bicycle-lamp. Fig. 2 is a central vertical section through a bicycle-lamp. Fig. 3 is a view in side elevation showing one of the charge-holders detached. Fig. 4 is a horizontal section on the line $x^4 x^4$ of Fig. 3. Fig. 5 is a central vertical section showing a form of bicycle-lamp containing some parts which differ in detail from the lamp shown in Fig. 2. Fig. 6 is a detail, partly in elevation, partly in section, and with some portions broken away, showing portions of the feeding devices employed in the lamp illustrated in Fig. 5. Figs. 7 and 8 are views in vertical section, showing modified forms of the expansible charge-holder; and Figs. 9 and 10 are views in elevation, illustrating different forms of table-lamps containing my invention.

In external appearance and in the general features of the construction the lamps illustrated in Figs. 1, 2, and 5 are substantially the same. The upper portion a of the lamp is of suitable form to serve as a water-receptacle and is shown as provided with a contracted neck a' , fitted with a plug a^5 , having a valve-seat a^6 . The parts a and a' have formed integral therewith an expanded portion a^2 , adapted to serve as the upper end of a generating-chamber. The part a^2 is provided with a packing-ring a^3 and a screw-threaded annular flange a^4 for receiving the shell f , which serves as the generating-chamber and the lower or body portion of the lamp. The upper end of the shell f is screw-threaded for engagement with the part a^2 above noted. The plug a^5 is screw-threaded to receive the lower screw-threaded end of a regulating-valve b , the stem of which passes out through a frictional packing-gland b^2 , which may be of rubber, and is provided with a handpiece b' on its exterior. The water-chamber a is also provided with an air-inlet a^7 . A feed-wick n is shown as mounted within a holder n' of pipe-like form within the water-chamber a , which holder or pipe opens to the water z' , near the bottom of the chamber, and then passes upward and around the top, and thence downward along the opposite side of the chamber, and terminates in the plug a^5 . The wick n extends through a suitable passage in the plug a^5 below the valve b , and thence downward through the plug and into a tube or pipe n^2 , fixed to the plug a^5 and depending therefrom in position to extend near to the bottom of the charge-holder when in working position within the shell or generating-chamber f .

The wick n is composed of absorbent material. The wick n is submerged within the water z' and extends through the lower open end of the depending tube n^2 in the generating-chamber, and said wick is of a size to completely fill the passages for the same in the plug a^5 and the tube n^2 .

The wick n is so disposed within the plug

a^5 as to be subject to a pinching action from the regulating-valve b .

The body portion or generating-chamber f of the lamp is shown as provided with a bracket-clamp $f' f^2$ for securing the lamp to a bicycle or other support. The shell f is also provided with a keeper f^3 to receive the spring-finger p^5 of the flame-chamber or bull's-eye shell p . The shell f is also provided with a burner f^4 , fitted with a gas-cock f^5 , which burner is of elbow form and has its tip projecting into the flame-chamber. The flame-chamber shell p is provided with chimney p' , reflector p^3 , and lens p^3 of any suitable construction.

Having regard to the form of charge-holder illustrated in Figs. 2, 3, and 4, the same is shown as composed of a cylinder made up of longitudinally separable sections g and end caps g^2 and g^3 . The cylinder-sections g have their longitudinal margins constructed to unite with lap-joints g' . The cap-sections g^2 and g^3 are flanged to tightly fit by friction over the ends of the cylinder made up of the parts g . One of the cylinder-sections g has sufficient spring in respect to the other to permit the said parts to hold together by friction when properly joined, and when the caps g^2 and g^3 are then applied to the cylinder all the parts of the shell will be firmly held together. The cap member g^3 is perforated at its center to pass the tube n^2 when the holder is in working position, and the lower cap g^2 is shown in Fig. 2 as provided with a perforated tube g^5 , rising from its center and open at its upper end, which tube g^5 is adapted to receive the tube n^2 , depending from the plug a^5 when the parts are in working position. Before applying the cap g^3 the shell is loaded by being partly filled with carbid z , as shown in Fig. 2, and placing over the same the other parts of the charge-holder. These other parts are a piece of blotting-paper or other absorbent material k' , placed directly over the top of the carbid, a follower k , placed directly over the blotting-paper k' , and a spring k^2 , placed over the follower k , with the blotting-paper, the follower, and the spring encircling the tube g^5 , which rises from the bottom of the holder. The top cap g^3 is then placed in position and the charge-holder is loaded or in cartridge form, adapted to be applied in working position by placing the same within the shell or body portion f of the lamp, and then applying to the shell f the upper or cap portion of the lamp made up of the parts carried with the water-chamber a , so to bring the same into the positions relative to each other. (Shown in Fig. 2.)

With the parts as illustrated in Fig. 2 the action would be substantially as follows: The regulating-valve b being properly manipulated to sufficiently relieve the wick n at the valve-seat a^6 , the water will be fed by the wick n under a capillary and siphon action and be delivered from the lower end of the wick in

a finely-divided form and be carried out by the air or by the flow of the water to the carbid z through the perforations in the tube g^5 . Then as soon as the reaction begins, which is 5 instantaneous, more or less of the moisture, under the action of the heat, will pass upward in the form of vapor or steam in the tube g^5 until it comes in contact and is taken up, more or less, by the disk k' of blotting-paper 10 or other absorbent material. This will again distribute the moisture in a further finely-divided condition to the top portion of the carbid. Assuming the gas-cock f^5 to be open, the gas will be free to pass out to the burner 15 f^4 and will be used substantially as fast as generated, assuming the valve b to be in proper position and the parts to be properly proportioned relative to each other.

Having regard to the form of charge-holder 20 illustrated in Figs. 5 and 6, the main or body portion r^3 thereof is shown as of cup-like form, open at its upper end and fitted with a cap-section r^4 , which makes a tight or frictional fit with the walls of the cup. The cap-section 25 r^4 of the holder is centrally perforated to pass the stem portion r of a feed-tube r' , the upper end portion of which is of funnel-like form, with a cylindrical rim-section r' , adapted when the parts are in working position to fit 30 over the plug a^5 of the lamp, which in this instance is extended farther into the generating-chamber of the lamp than as shown in Fig. 2. The lower end of the feed-tube r' is closed, and the tube r' is wrapped or otherwise 35 incased with a body of blotting-paper or other absorbent material r^2 . Outside the blotting-paper r^2 is preferably placed a wire-gauze sleeve r^8 . The tube r is perforated. In loading this form of charge-holder (illustrated in Figs. 5 and 6) the cup portion of the shell is partly filled with carbid. The follower k , with or without the disk of blotting-paper k' underneath the same, is then applied 40 to the top of the carbid. The spring k^2 is placed on the follower k , and the feed device (made up of the parts r , r' , r^2 , and r^8) is applied after the cap r^4 has been placed in position at the top of the cup. The charge-holder 45 is then in cartridge form and is ready for application to the lamp. This is done by placing the same within the shell or body portion f of the lamp and applying the latter to the top portion of the lamp, with the upper end r' of the feed-tube in engagement with 50 the lower end of the plug a^5 , as shown in Fig. 5. With this form of charge-holder the plug a^5 is fitted with a needle-valve r^6 for controlling the supply of the water. Ports r^7 lead 55 to the seat of the needle-valve r^6 . Having regard to the action, the needle-valve r^6 is properly set to afford a properly-regulated supply of water, which will pass by gravity into the tube r and thence out into the blotting-paper or other absorbent material r^2 , 60 which will distribute the same to the carbid in a finely-divided condition. In this instance it will be noted that the blotting ma-

terial r^2 around the feed-tube r is in direct and extended contact with the carbid. The water-supply of course should be regulated to 70 be kept within the limit of saturation of the absorbent material r^2 .

The charge-holder illustrated in Fig. 7 is similar in construction and in action to that illustrated in Figs. 5 and 6, with the exception that the perforated feed-tube has its section s fixed below to a disk s' , fitting the shell or body portion of the holder, and the cap r^4 of the shell has a central perforation of sufficient size to pass the enlarged upper end portion of the feed-tube. This is to facilitate 75 cleaning of the shell in case it be desired to reuse the same. With the form of charge-holder illustrated in Fig. 7 the tube, with its disk s' , is first placed in position within the body of the shell before the shell is loaded with carbid. Then the other parts are applied as described in connection with the form 80 illustrated in Fig. 5.

In the form of charge-holder illustrated in 85 Fig. 8 the body portion r^3 and the cap r^4 are of the same form and occupy the same relation as in the form of holder shown in Fig. 5; but the follower k is shown as provided with a multiplicity of perforations k^3 and below 90 the same is applied to the top of the carbid (not shown) a body of blotting-paper or absorbent material k' , and above the follower k and underneath the cap r^4 is placed a body of sponge or other compressible absorbent material t , which when saturated will expand 95 more or less, and from which the water may be forced to a greater or less extent by compression. With the form of charge-holder 100 shown in Fig. 8 the body of sponge or other compressible or absorbent material t itself affords a yielding part which will to a limited extent perform the same function as the spring k^2 , shown as embodied in the other charge-holders. The action is not materially 105 different, with the exception that the water would be delivered directly from the needle-valve seat to the sponge t and from the sponge through the perforated follower k to the blotting-paper k' and be by this distributed to 110 the carbid. A further difference would arise from the fact that as the follower k would move upward under the increase of bulk from the slaked carbid, the sponge would be compressed more or less, and thereby afford an 115 increased water-feed, which would in a measure 120 compensate for the absorbing qualities of the residue and possibly insure a steadier light.

The charge-holder, as illustrated in Figs. 5, 125 6, and 7, is to be preferred over the forms illustrated in the other views.

It is obvious that all the charge-holders illustrated are adapted to be preloaded and then to be applied in working position within 130 the lamp or other generator and there afford a yielding part, or, in other words, be expandable, so as to hold the carbid at all times in a compact body, while permitting the

increase of bulk due to the change of form under the reaction. It is further obvious that these charge-holders might all be preloaded and be hermetically sealed by a suitable 5 wrapper in any suitable way for storage and shipment, ready to use at distant points. The charge-holder of course might take other forms than those shown as long as it had the expandible feature and adaptation to pre-10 loading for use as a cartridge.

In the student-lamp illustrated in Fig. 9 the generator *v* is mounted for vertical adjustment on a supporting-standard *v*⁴, fitted with the customary clamp *v*³. The generator *v* is provided with a gas-pipe *v*² and burner *v*', to which is applied the customary shade *v*⁵. The generator *v* is of proper construction to afford a water-receptacle at its top to supply the feed-water in substantially the same way 15 as in the lamp illustrated in Fig. 5, has a removable bottom, preferably of cup-like form, and is of such construction as to permit any of the charge-holders shown in Figs. 2, 5, 7 20 or 8 to be used therein.

In the hand-lamp shown in Fig. 10 the generator *w* is shown as provided with a gas-pipe *w*', having burner *w*², and this lamp is of such construction as to afford a water-receptacle at its top for supplying the regulated quantity 25 of water to the carbid, and is also provided with a removable bottom through which the charge may be applied. It was noted that the water-receptacle *a* had an opening *a*⁷ to the atmosphere.

In all the lamps described any excessive 30 gas which may tend to accumulate in the generating-chamber beyond what can be properly consumed at the burner can escape to the atmosphere by passing upward through the feed-water passage and then through the body of water in the chamber *a* and out to the atmosphere through the air-hole *a*⁷. This serves two functions: it prevents excessive overgeneration and checks the flow of the feed-water automatically. This feature is 35 identical in action with that disclosed and broadly claimed in my prior patent, No. 621,217 of date March 14, 1898, in claim 6 thereof.

It should be noted that in all the charge-holders herein disclosed the absorbent material employed to receive, drink up, and then distribute the feed-water to the carbid is not only in direct and extended contact with the 40 carbid, but is disposed across the water-inlet thereto, so that the water can only reach the carbid by first passing through the absorbent material.

What I claim, and desire to secure by Letters Patent of the United States, is as follows:

1. In an acetylene-gas generator, the combination with a chamber for carbid calcium, of a yielding, movable part, which confines the carbid and residue in a compact body, 45 which yields on the expansion of the carbid due to its decomposition, and means for sup-

plying a regulated quantity of water to the carbid.

2. As a new article of manufacture, an expandible charge-holder adapted to be pre-70 loaded with carbid and to be handled as a cartridge for charging a lamp or other generator, substantially as described.

3. In a generator adapted to generate gas from a liquid and a solid gas-producing substance, a chamber to contain the solid and a liquid-reservoir, a body of absorbent material adapted to be saturated with the liquid gas-producing substance, and having direct and extended contact with the solid gas-producing substance, and a controllable liquid-inlet for supplying a regulated quantity of liquid to said absorbent material, whereby the said absorbent serves to limit and distribute said liquid to said solid, substantially as described. 85

4. A charge-holder for acetylene-gas lamps, or other generators, containing carbid and having an absorbent material in direct contact with the carbid and across the line of the water-feed thereto, substantially as described. 90

5. An expandible charge-holder, for acetylene-lamps or other generators, containing carbid and an absorbent material in direct contact with the carbid, and across the line of the water-feed thereto, substantially as de-95 scribed.

6. In an acetylene-gas generator, the combination with a chamber for the carbid, of a movable part and a spring which coöperate to hold the carbid and residue in a compact 100 mass, under yielding pressure, and to permit the same to expand, under the increase of bulk, when the carbid slakes, and means for affording a regulated supply of water to the carbid, substantially as described. 105

7. In an acetylene-gas lamp or other generator, the combination with a movable part and a spring coöoperating to hold the carbid and its residue in a compact mass, within the generating-chamber, under a yielding pressure, of a body of absorbent material in direct contact with the carbid and across the water-inlet, and means for affording a regulated supply of water to said absorbent material, substantially as described. 110

8. In a generator adapted to generate gas from a liquid and a solid gas-producing substance, a chamber to contain the solid and a liquid-reservoir, a body of absorbent material adapted to be saturated with the liquid gas-producing substance, with the same disposed in the form of a tube extending through or substantially through the body of carbid, for affording direct and extended contact therewith, and a controllable inlet for supplying a regulated quantity of liquid to said absorbent material, substantially as and for the purposes set forth. 115

9. In a generator of the class described, the combination with a carbid-holder having a 120 movable part adapted to pass water and subject to the pressure from the expanded prod-

ucts of decomposition, of a sponge or other body of compressible absorbent material confined and subject to compression under the expansion of said products, when the parts 5 are in working position, substantially as described.

10. In a lamp or other acetylene-gas generator, a fount or generating-chamber containing carbid or similar matter, a perforated 10 water-feeding tube traversing said chamber, and a spring-controlled cap or follower sur-

rounding said tube and adapted to compress or compact the carbid in said chamber, yet yielding in the expansion of said carbid due to its decomposition, substantially as and for 15 the purposes set forth.

In testimony whereof I affix my signature in presence of two witnesses.

LEROY S. BUFFINGTON.
